(57) CLAIM

The ornamental design for a laser light, as shown and described.

DESCRIPTION

FIG. 1 is a perspective view of a laser light.

FIG. 2 is a front elevation view of the laser light of FIG. 1.

FIG. 3 is a rear elevation view of the laser light of FIG. 1.

FIG. 4 is a side elevation view of the laser light of FIG. 1.

FIG. 5 is the other side elevation view of the laser light of FIG. 1.

FIG. 6 is a top plan view of the laser light of FIG. 1.

FIG. 7 is a bottom plan view of the laser light of FIG. 1.

FIG. 8 is a perspective view of a laser light showing a second embodiment of the design.

FIG. 9 is a front elevation view of the laser light of FIG. 8.

FIG. 10 is a rear elevation view of the laser light of FIG. 8.

FIG. 11 is a side elevation view of the laser light of FIG. 8.

FIG. 12 is the other side elevation view of the laser light of FIG. 8.

FIG. 13 is a top plan view of the laser light of FIG. 8; and,
FIG. 14 is a bottom plan view of the laser light of FIG. 8.
The broken line showing on the drawing depict portions of
the laser light that form no part of the claimed design. The
power cord is shown broken away for ease of illustration
only.
